UNITED STATES PATENT OFFICE.

WILLIAM U. GRIFFITHS, OF PHILADELPHIA, PENNSYLVANIA.

WATER-CLOSET APPARATUS.

No. 901,438.

Specification of Letters Patent.

Patented Oct. 20, 1908.

Application filed December 21, 1905. Serial No. 292,764.

To all whom it may concern:

Be it known that I, WILLIAM U. GRIFFITHS, a citizen of the United States, residing in the city and county of Philadelphia, State of Pennsylvania, have invented certain new and useful Improvements in Water-Closet Apparatus, of which the following is a specification.

My invention relates to water closet apparatus, and more particularly to that class of apparatus which is adapted to be located "out-doors", where it is unprotected from the cold of the winter. It is necessary in such cases that the flush tank and other parts of the apparatus which ordinarily are filled with water shall be free from water so that the parts do not become frozen together and thus inoperative.

My invention relates specifically to an improvement of the means for occasioning the closing of the port which opens from the flush tank into the flush pipe of the apparatus at such times as it is desired to fill the tank preparatory to flushing the closet.

In order that my invention may be more readily understood, reference is to be had to the accompanying drawing forming a part of the specification.

In the drawings, 1 designates a closet hopper and 2 designates a flush tank, the interior of which is in communication with the upper edge of the hopper by means of the flush pipe 3.

4 designates a port in the bottom of the flush tank which is adapted to be closed by means of a valve 5 located below the bottom of the tank. The valve 5 is pivotally connected to a rod 8 which in the particular construction shown is supported in bearings 9 upon the tank 2, and has a portion bent laterally over the said tank to which laterally bent portion the valve 5 is connected.

In the construction shown, the rod is bent twice and one end thereof extends to a point a short distance above the upper surface of the bottom of the tank, but, of course, it will be understood that it is unnecessary to extend the rod to this point and that the valve may be connected to the rod 8 by lengthening what may be termed the shank 10 of the valve to a point near the top of the tank at which point the connection between the valve and the rod 8 may be effected.

It will be observed that the portion of the rod within the tank is supported and guided in guides 11. The lower end of the rod 8 ex-

tends to a point a slight distance above the rear end of an arm 12 which is connected to the closet seat 13 and which is adapted to move upwardly as the seat is moved downwardly. The rear end of the arm 12 and the lower end of the rod 8 are so related to each other that when the seat is moved downwardly into contact with the upper edge of the closet hopper, the rod is lifted by the upward movement of the said arm to an extent sufficient to carry the valve 5 into contact with the lower side of the bottom of the flush tank 2 to close the port 4.

Water enters the flush tank 2 through a pipe 14. When the closet seat is moved down upon the upper edge of the closet hopper, it contacts with a rod 6, the lower end of which is connected to a valve 15. The said rod 6 is pressed upwardly so as to hold the valve 15 in closed position by means of a coiled wire spring 7.

Normally, as will be seen, the seat 13 is located above and out of contact with the upper edge of the closet hopper. When it is moved down upon the hopper, it strikes the rod 6 and occasions movement thereof downwardly to open the valve 15 to permit water to pass through the opening or passageway 16 from the water supply pipe 17 to the pipe 14 from which it escapes into the flush tank 2.

In order that the water may flow out of the pipe 14 when the apparatus is not in use, I have provided a short pipe construction 18 between the soil pipe 19 leading from the water closet hopper to the valve mechanism with the interior of which the pipe 14 communicates through a passageway 20. During the time that water is flowing through the pipes 17 and 14 into the flush tank 2, the passageway 20 is closed by means of a valve 21.

In order to prevent the water from overflowing the tank in case the valve 15 should be held down for a longer time than is usually the case, I have provided an overflow pipe 22 located in the said tank and emptying into the flush pipe 3.

It will be seen that I have provided a water closet apparatus which is admirably adapted for out-door use, and which is simple and economical.

Having thus described my invention, I claim:

1. In a water closet apparatus, in combination, a flush tank having a port therein, a water closet hopper having communication

- with the said flush tank, a water closet seat having an arm, a rod having its lower end so positioned with relation to the said arm that it is adapted to be engaged thereby, and a portion of the said rod extending over the said tank, and a valve connected to the portion of the said rod which extends over the said tank, the said valve being adapted to close the said port in the flush tank.
- 10 2. In a water closet apparatus, in combination, a flush tank having a port or opening, a water closet hopper in communication with the said flush tank, a water closet seat having an arm, a rod, the lower end of which is located in proximity to the said arm and is adapted to be engaged thereby when the said arm is moved upwardly, and the upper portion of the said rod being bent laterally and downwardly to a point above the upper surface of the bottom of the tank, and a valve connected to the downwardly bent portion of the said rod within the tank, the said valve being located below the bottom of the tank and being adapted to be moved upwardly by an upward movement of the rod to close the said port.
- 15 3. In a water closet apparatus, in combination, a flush tank having a port, a water closet hopper in communication with the said tank, a closet seat having an arm extending rearwardly therefrom, which arm is adapted to move upwardly when the seat is moved down upon the upper edge of the hopper, a rod, the lower end of which is located in proximity to the rear end of the said arm and is adapted to be engaged thereby and moved upwardly by the said arm, the upper end of the said rod being bent or extended over the upper edge of the tank, means for 20 slidably supporting the said rod upon the said tank, a valve connected to the portion of the said rod which is extended over the said tank, the said valve being adapted to close the said port when the rod is moved upwardly.
- 25 4. In a water closet apparatus, in combination, a flush tank having a port, a water closet hopper in communication with the said tank, a water closet seat having an arm, a rod, the lower end of which is located in proximity to the outer end of the said arm and is adapted to be engaged thereby and moved upwardly as the seat is moved into contact with the upper edge of the hopper,
- the upper portion of the said rod being bent laterally and downwardly into the said flush tank; a valve connected to the downwardly bent portion of the said rod and moving upwardly with the rod to close the port or opening, a water supply pipe for supplying water to the said tank, a valve which normally closes the said pipe, and means intermediate the said valve and the water closet seat whereby when the seat is moved in a position upon the upper edge of the water closet hopper the said last mentioned valve is opened to permit the passage of water into the said tank.
- 30 5.. In a water closet apparatus, in combination, a flush tank having a port therein, a water closet hopper having communication with the said flush tank, a water closet seat having an arm, a rod having its lower end so positioned with relation to the said arm that it is adapted to be engaged thereby so that the said rod may be raised by an upward movement of the said arm, the said rod being bent and having a portion extended over the top of said tank, and a valve located underneath the bottom of the tank and connected to the portion of the said rod which extends over the said tank, the said valve being adapted to close said port in the flush tank when the rod is raised.
- 35 6. In a water closet apparatus, in combination, a flush tank having a port or opening, a water closet hopper in combination with the said flush tank, a water closet seat having an arm, a rod, the lower end of which is located in proximity to the said arm and is adapted to be engaged thereby when the said arm is moved upwardly whereby the said rod is raised and the upper portion of the said rod being bent laterally and downwardly, and a valve connected to the downwardly extended portion of the said rod, the said valve being located below the bottom of the tank and being adapted to be moved upwardly to close the said port by an upward movement of the said rod.
- 40 7. In testimony that I claim the foregoing as my invention, I have hereunto signed my name this 27th day of Nov. A. D. 1905.
- 45 WILLIAM U. GRIFFITHS.
- In the presence of—
S. SALOME BROOKE,
LAURA KLEINFELDER.
